UNITED STATES PATENT OFFICE.

ARON W. ROCKEY, OF LINEVILLE, IOWA.

CHICK FEEDER.

Application filed March 2, 1922. Serial No. 540,537.

To all whom it may concern:

Be it known that I, ARON W. ROCKEY, a citizen of the United States, residing at Lineville, in the county of Wayne and State of Iowa, have invented certain new and useful Improvements in Chick Feeders, of which the following is a specification.

The present invention relates to means for giving free access of small chicks to food, while preventing older fowls securing the same. The object is to provide a novel, and at the same time practical and inexpensive structure for this purpose.

In the accompanying drawings:—

Figure 1 is a side elevation of one embodiment of the invention,

Figure 2 is an end elevation of the same,

Figures 3, 4 and 5 are cross sectional views, respectively, on the lines 3—3, 4—4 and 5—5 of Figure 1,

Figure 6 is a detail perspective view of the device for excluding chicks from the feed trough.

In the embodiment disclosed a body is employed comprising a base-board 7 on which are mounted gabled end walls 8. Said end walls support a roof, comprising side sections 9 and 10 that are hinged together as illustrated at 11, one of the sections, as 9, being provided with a handle 12, by which the feeder may be carried. The section 9 is provided at its ends with flange plates 13 that overhang the outer sides of the end walls 8 and have pintles 14 passing therethrough, said pintles constituting hinge connections between the roof and the said end walls. A transverse partition or supplemental end wall 15 is located between the outer end walls 8, and a hook 16, carried by the roof section 9, is adapted to engage over a pin 17 on said partition to hold the section 9 in place. The other section 10 is secured by a hook 18 carried by one end of the same and engaging over a pin 19 on one of the end walls 8.

It will be noted by reference to Figures 1, 3, 4 and 5 that the sides of the body are open and the space between the base plate 7 and eaves of the roof is such that it will permit the passage of small chicks while preventing the entrance of larger fowls.

Between one of the end walls and the partition 15 is mounted a feed trough 20, the sides of which terminate short of the

sides of the walls and the upper edges are spaced from the roof. The remaining space within the body between the partition 15 and the other end wall 8 may be used as a holder or compartment 21 for a water font. The opposing sides of the end wall 8 and partition 15 between which the trough 20 is located are provided with downwardly converging grooves 22 adapted to receive removable boards 23 forming a hopper or reservoir for dry mash or the like. It will be noted that when these boards are in place and the roof 9—10 is thereover, this hopper is substantially closed at its upper end, but that space is afforded the chicks to permit their access to the feed in the trough 20. If wet mash is employed the hopper boards 23 are removed and a bar 24 is employed to prevent the chicks standing in the trough 20. This bar is provided at one end with a tenon 25 adapted to be inserted in a groove 26 in the partition 15, while its opposite end on said bar has a pin 27 that is first inserted in a socket 28 formed in the end wall 8.

It will be clear that access to the trough 20 and to the hopper 23 and the utilization of said hopper boards or of the bar 24 can be easily had by removing the cover or roof from the body, and when either the arrangement shown in Figure 3 or that illustrated in Figure 4 is employed, small chicks have ready access to feed in the trough 20, while grown fowls are prohibited from entrance thereto. The device is one that can be cheaply constructed and can be readily carried about.

From the foregoing, it is thought that the construction, operation and many advantages of the herein described invention will be apparent to those skilled in the art without further description, and it will be understood that various changes in the size, shape, proportion and minor details of construction may be resorted to without departing from the spirit or sacrificing any of the advantages of the invention.

Having thus fully described my invention, what I claim as new, and desire to secure by Letters Patent, is:—

1. A chick feeder comprising a base, end walls, a roof having its lower edges spaced from the base a sufficient distance to permit the passage of small chicks only, a trough beneath the roof, and a transverse

partition, one end wall and the partition being provided with means for receiving a removable reservoir and a removable device for preventing entrance of chicks to the trough.

2. A chick feeder comprising a base, end walls, a roof having its lower edges spaced from the base a sufficient distance to permit the passage of small chicks only, a trans-
10 verse partition, a feed trough extending be-

tween the partition and one end wall, and means for interchangeably supporting above the trough a reservoir or a means for preventing chickens from entering the trough.

In testimony whereof, I affix my signature in the presence of two witnesses.

ARON W. ROCKEY.
